APPARATUS FOR LIFTING STACKS OF
BRICKS AND THE LIKE

Herbert J. Neher, Decatur, Ala.

Application August 25, 1951, Serial No. 243,730

14 Claims. (Cl. 294—63)

1

My present invention relates to apparatus for lifting stacks of objects such as bricks, concrete blocks, similar building units and the like, and has for an object the provision of such apparatus embodying a main frame having portions disposed to lie alongside and over the stack, a set of grippers operatively carried by the main frame movable laterally of the stack toward each other to grip the stack therebetween, together with means connected to the grippers effective to cause the grippers to move evenly and concomitantly into clamping engagement with the stack.

A more specific object of my invention is to provide brick handling apparatus embodying a main frame formed of L-shaped sections held in spaced relation to each other by suitable members and disposed for one leg thereof to overlie the stack and for the other leg to stand vertically at one side thereof, a stack gripper frame comprising a plurality of sets of vertical arms disposed on opposite sides of the stack, the sets of corresponding gripper arms being movable toward each other by means of links pivotally connected to the arms at their outer ends and connected to vertically movable members at their inner ends, each of the sets of arms being provided with co-acting guide members effective to cause the same to move toward each other, all of the sets of grippers being actuated through a vertically movable equalizing bar and cable arrangement, whereby upon upward movement of the equalizing bar all of the sets of grippers contact the stack with equal pressure, effectively gripping the stack for lifting the same.

Another object is to provide apparatus of the character designated in which each of the oppositely disposed sets of gripper arms are moved toward each other by means of independently movable sheave blocks operatively connected to the inner ends of the links, the sheaves being connected to the equalizing bar by means of a rope or cable passing under the sheaves and over sheaves or rollers carried by the equalizing bar.

Another object is to provide brick handling apparatus in which other sets of grippers are provided for engaging the ends of the stack and in which these grippers are automatically opened to receive the stack and automatically engage the stack as the apparatus is lifted, thereby preventing the bricks at the ends of the stack from falling off when the stack is raised.

Further objects of my invention are to provide apparatus of the character designated which shall be simple and durable of construction; in which the number and complexity of the parts

is reduced to a minimum, thus making the apparatus suitable for use under the rugged conditions encountered around brick yards; to provide simple, manually engageable means to lock the grippers in open, stack receiving position, which means is automatically disengaged when the apparatus is lowered about the stack; and to provide vertically slideable gauges on portions of the main frame nearest the operator of the lift truck or other means used to raise the apparatus by means of which the apparatus may be quickly and accurately centered over a stack, facilitating the placing of the same about the stack.

15 Apparatus illustrating the features of my invention is shown in the accompanying drawings forming a part of this application in which:

Fig. 1 is a side elevational view of my improved brick handling apparatus mounted on the lift structure of a lift truck and shown in place about a stack of bricks, the gripping frame being in open position;

Fig. 2 is a rear elevational view taken generally along line II—II of Fig. 1, portions of the lift truck mechanism being shown in section;

Fig. 3 is a side elevational view of the apparatus in raised position, preparatory to being lowered about a stack of bricks;

Fig. 4 is a fragmental end elevational view showing the device lowered about a stack of bricks and with the grippers clamped about the stack;

Fig. 5 is an enlarged, fragmental detail sectional view taken generally along line V—V of Fig. 1;

Fig. 6 is a detail sectional view taken generally along line VI—VI of Fig. 5;

Fig. 7 is a fragmental detail view taken along line VII—VII of Fig. 1, the view being enlarged for the sake of clarity; and,

Fig. 8 is a detail sectional view taken along line VIII—VIII of Fig. 7.

Referring now to the drawings for a better understanding of my invention and more particularly to Fig. 1, I show my improved apparatus associated with a lift truck 10. In the manner understood, the truck 10 comprises a vertical column 11. Slidably within the column 11 is a block or the like 12 which may be raised and lowered by means of a hydraulic cylinder 13. Projecting forwardly of the block 12 and carried thereby is a boom 14 which may be rigidly braced by a suitable knee brace 16. Means, not shown, are provided for supplying fluid under pressure to the lower end of cylinder 13, thereby to raise the boom 14 vertically.

3

My improved brick handling apparatus comprises a main or supporting frame indicated generally by the numeral 17. The frame 17 may comprise integrally formed, L-shaped sections each of which comprises a rear vertical leg 18 and a horizontal base section 19. It will be noted that there are two of the main frame sections 17 and that they are held in spaced relation by means of lateral angles 22 and 23. The lower ends of the legs 18 are disposed to rest on the surface supporting the stack when the device is placed about a stack of bricks indicated by the letter S.

Secured to the horizontal base portions 19 of the main frame sections 17 are upstanding, spaced apart guide members 24 and 26. The upper ends of the sets of upright members 24 and 26 may be cross-braced by plates 27. The sets of members 24-26 may be cross connected by means of a bar 28 secured thereto as by means of bolts 29.

The gripping frame for my improved apparatus comprises a plurality of spaced apart arms 31 formed of steel bars or the like. As illustrated in Figs. 1, 3 and 4 the arms 31 converge inwardly from the top to the bottom so that in the manner later to be explained the lower ends thereof contact the lower course of bricks in the stack S. The inner faces may be provided with half round gripping pads 31a at the lower ends of the arms 31. On the front side of the apparatus are a similar set of gripping members indicated by the numeral 32, which also slope inwardly as illustrated and which may carry half round pads 32a at the lower ends thereof. The corresponding gripping arms 31 and 32 are substantially aligned transversely of the stack S and I preferably provide a front and rear arm for each of the individual bricks or the like forming the lower course as is illustrated in Fig. 2.

The rear arms 31 of the gripping frame each carry a horizontal, inwardly extending rod 33 made fast as by welding to the inner side thereof. The front legs 32 each carry a horizontally disposed, inwardly extending tube 34, likewise made fast to the inner side thereof as by welding. Rods 33 fit snugly and slidably within the tubes 34 for a purpose later to be explained.

Secured to the inner faces of each of the front and rear legs, just beneath the rods or tubes carried thereby are horizontally disposed lengths of tubing 36. (See Figs. 7 and 8.) The lengths of tubing 36 may be welded to the inner sides of the legs 31 and 32 to form a bearing. At each end of each of the lengths of tubing 36 are inwardly directed links 37 and 38. Headed pins 39 pass through suitable openings in the links and thence through the tubes 36 and are held in place by means of cotter pins or the like 41. It will thus be apparent that each of the arms 31 and 32 is provided with a pair of links 37 and 38 which are pivotally connected thereto by means of the tubes 36 and the pins 39. The inner ends of each of the sets of links 37 and 38 are pivotally connected by means of pins 40 and 42 to clevises 43 and 44 which depend from the sides of sheave blocks 46. The clevises are disposed to straddle the tubes 34 when the apparatus is lowered about a stack of bricks as will later become apparent. In each of the blocks 46 is a sheave 47, journaled on a suitable bearing pin 48. The tubes 34 are secured to the lateral angle 22 of the main frame 17 by means of straps 45 which are welded to the tubes and bolted to the laterally extending angle 22.

4

Slidable vertically between the uprights 24 and 26 is an equalizing bar indicated generally by the numeral 49. The equalizing bar 49 comprises parallel, spaced apart bars 51 and 52 which are cross connected by a plurality of bolts 53 and which may be held in spaced relation by any suitable means, not shown. Mounted for rotation on the bolts 53 are sheaves 54 which are so spaced longitudinally of the equalizing bar 49 as to lie approximately midway between adjacent ones of the sheave blocks 46. Secured to a rivet 56 or the like passing between the bars 51 and 52 is one end of a flexible member 57 such for instance as a cable or wire rope. As illustrated in Fig. 2 the cable 57 is threaded alternately under the sheaves 47 and over the sheaves 54 and finally is secured to a rivet 58 at the opposite end of the equalizing bar 49.

Mounted for oscillation in bearings 59 and 61 carried on top of the sets of uprights 24-26 is a cross shaft 62. Secured to the shaft 62 and extending outwardly and downwardly thereof on the side of the apparatus toward the lift truck 10 are bars 63 and 64. On the opposite side and extending in an opposite direction from the bars 63 and 64 is a third bar 66, the purpose of which is to counterweight the bars 63 and 64 to bias the same to the position illustrated in Fig. 1.

Secured to the top of the shaft 62 is a short length of bar 67. Fastened to the top of the bar 67 is a rope or the like 68 which is placed in reach of the operator of the lift truck 10.

In order to assure that bricks at the end of the stack do not fall off while the stack is being moved, I provide end gripping means which will now be described. Since the grippers at each end are identical, a description of one will suffice for both. At each end of the stack S I provide depending grippers in the form of bars 69. The bars preferably are so spaced that each one engages the bricks of the uppermost courses. Since the lowermost course is clamped by the main gripper arms, it is not necessary that the end grippers engage the lowermost course. The bars 69 are secured at their upper ends to an angle 71. Secured to the angle 71 and projecting over the stack S in a length of flat steel stock 72. The flat plate 72 passes slidably through straps 73 and 74 secured in any suitable manner to the upper side of a relatively large rectangular section of plate 76. The plates 76 at each end of the apparatus are cross connected by lengths of plate 75. As will be later explained the plate 76 and the cross plate 75 are adapted to rest upon the upper course of bricks when the device is lowered thereover. Fitting loosely over the superjacent one of the tubes 34 are U-shaped straps 77 and 78 which are secured at their lower ends to the plate 76.

Secured to the inner end of the plate 72 is a cross member 79. Tension springs 81 and 82 have their ends secured to the strap 73 and to the bar 79 as shown in Fig. 6. A pair of other tension springs 83 and 84 are secured at 85 and 87 to the angle 71 and at their opposite ends are secured to the ends 88 and 89 of a flexible tension member such as a cable 91. The cable 91 passes under the centermost one of the cross tubes 34 and may be secured to the superjacent one of the pins 40 or 42 passing through the clevises 43 and 44 of the centermost sheave block 46.

Mounted slidably about the main frame legs 18 are plate members 92. The members 92 may comprise a lower inwardly bowed section 93 and

an upper generally flat section 94. The members 92 may be held slidably about the legs 18 by means of straps 96 as illustrated in Figs. 1 and 2. Limit chains 97 may be provided to limit downward sliding movement of the members 92, all for a purpose which will presently be more definitely set forth.

Referring more particularly to Figs. 1 and 2, the equalizing bar 49 may be operatively connected to the boom 14 of the lift truck by means of a cross bar 98 carried by the boom 14. Depending from the ends of the lift bar 98 are cables 99 and 101 which pass loosely through suitable openings 102 and 103 in the plates 21. The lower ends of the cables 99 and 101 may be connected to the equalizing bar 49 by means of clevis shaped straps 104 and 106.

On the arms 31 nearest the ends of the apparatus I may provide auxiliary gripping means for preventing the end bricks of the lower course from falling out when the stack is raised. These members may comprise leaf springs 107 which are welded to the outer edges of the arms 31 for a portion of their length near the top thereof. The lower ends of the same may be bent inwardly toward the stack S as shown clearly in Figs. 1, 3 and 4. The purpose of these spring fingers is to grip the end bricks of the lower course more firmly so that when the arms 31 move inwardly to clamp the stack these end bricks are not permitted to twist and fall from the gripping units.

From the foregoing the method of constructing and using my improved apparatus may now be explained and understood. With the apparatus assembled on a lift truck or like apparatus so that power for lifting the same may be applied to the equalizing bar 49, it will be apparent that if the device is resting on the ground or other surface, not surrounding a stack of bricks, the entire apparatus is supported by the legs 18 and the front gripping arms 32. In this position, by further lowering the boom 14 the weight of the parts, including the sheave blocks 46, the tubes 34, rods 33 and the links 38 causes the links themselves to assume the position shown in Figs. 1 and 2. Downward movement of the sheave blocks 46 is limited by the same coming to rest on top of the guide tubes 34. In this position it will be apparent that the gripping arms 31 have moved outwardly, away from the forward arms 32. It will be apparent also that the cables 91 are slackened, permitting the tension springs 81 and 82 to move the plate 72 outwardly, thus moving the end gripping members 69 away from each other. With the device thus opened the operator pulls on the rope 68, rocking the bars 63 in position to be engaged by the equalizing bar 49 when lift is next applied to the equalizing bar through the cables 99 and 101. The operator now raises upwardly on the boom 14, causing the equalizing bar to come chock-a-block with the two bars 63 and 64, locking the apparatus in open position. Upon further upward movement of the boom 14 the entire apparatus is raised off the ground and is now ready to be placed about a stack of bricks S to be lifted. It will be noted that as soon as the legs 18 clear the ground the plate members 92 move downwardly so that they project below the ends of the legs 18 as illustrated in Fig. 3. The operator now moves the apparatus to a stack of bricks S and by eye centers the same to the right or left of the stack. By moving the tractor or lift truck forwardly until the plates 92 contact the rear side of the stack as shown in

Fig. 3, the operator is assured that the device is centered over the stack in the fore and aft direction. Having thus centered the apparatus he now lowers the boom 14, straddling the stack as illustrated in Fig. 1. As soon as the lower ends of the curved portions 93 of the plates 92 contact the ground they slide upwardly. When the apparatus is lowered onto the stack it is supported from the top thereof on the plates 75 and 76. Upon further slackening of the cables 99 and 101, gravity moves the equalizing bar 49 downwardly, out of contact with the bars 63 and 64. The unbalanced weight of the bar 66 then causes the shaft carrying all of the bars to rock so that the bars occupy the position shown in Fig. 1. The operator now raises the boom 14, putting tension on cables 99 and 101, thus moving the equalizing bar upwardly. This moves all of the sheave blocks 46 upwardly through the medium of cable 57, moving the inner ends of the links 38 upwardly in response thereto. This causes the rods 33 to telescope further into the tubes 34, bringing the rear arms 31 and the arms 32 into contact with the lower course of the bricks at the front and rear sides of the stack. Simultaneously with this movement cables 91 are tightened, putting tension on springs 83 and 84, thus moving the end gripping members 69 into engagement with the ends of the stack. Continued lift on the equalizing bar 49 causes the arms 31 and 32 to firmly grip the lower course of bricks, whereby the stack may be lifted clear of the ground and moved from place to place. Likewise, the end gripping members 69 grip more tightly as the centermost sheave block moves upwardly through the medium of the cables 91. The springs 83 and 84 form a resilient connection between the end grippers and their cables, preventing damage to the parts.

It will be especially noted that due to the equalizing bar arrangement and the individual sheave blocks for the front and rear sets of gripping arms, I assure that that part of the lifting force transmitted into clamping force is exerted equally on all of the sets of arms. Further, the tube and rod arrangement assures accurate guiding of the arms toward one another and makes the machine extremely rigid and durable. The legs 18 of the main frame serve to hold the lower ends of arms 31 clear of the surface supporting the stack, permitting these arms to move inwardly.

From the foregoing it will be apparent that I have devised an improved apparatus for handling stacks of brick, concrete blocks, and similar objects. In actual practice I have found that my invention is practical in every way and that it is simple of construction and economical of manufacture. It will be noted that the cross bar 28 extending between the uprights acts as a stop for the bars 63 and 64 in response to oscillation of the shaft 62 so that these bars are centered over the equalizing bar whenever the rope 68 is pulled.

My invention is particularly adapted for use in picking up a stack of bricks or the like from a yard and placing the same in a vehicle. Thus, a single lift truck equipped with one of my improved stack lifting machines can quickly load trucks calling at a brick yard or the like by picking up the stacks and setting them on the body of the truck. Due to the fact that I provide sets of gripper arms equal in number to the number of individual units in the lower course of the stack, I do not have to stack the bricks on pallets

or the like or to leave spaces therebetween for the entry of tine arms or the like. Further, my improved apparatus is effective in lifting a given number of courses of stacked objects from the top of a high stack thereof as well as for lifting an entire stack placed on the ground or other supporting surface.

While I have shown my invention in but one form, it will be obvious to those skilled in the art that it is not so limited but is susceptible of various changes and modifications without departing from the spirit thereof, and I desire, therefore, that only such limitations shall be placed thereupon as are specifically set forth in the appended claims.

What I claim is:

1. In apparatus for lifting a stack of bricks and the like, a main frame embodying vertical members disposed at one side of the stack and horizontal members overlying the stack, stack gripping means comprising sets of vertically disposed gripping arms with one arm of each set disposed on the same side of the stack as the vertical members of the main frame, coacting gripping arm guide means overlying the stack some of which are secured to the main frame and holding the arms for slidable movement toward and from the stack, means connecting the gripping arms to said guide means at points above the top of the stack, links pivoted to the gripping arms beneath the points of connection therewith of the associated guide means and extending inwardly over the stack, upwardly movable means connected to the inwardly extending ends of the links, and means engaging the upwardly movable means and adapted to raise the same thereby bringing the gripping arms into contact with the stack.

2. In apparatus for lifting a stack of bricks and the like, an L-shaped frame having legs disposed substantially vertically alongside and substantially horizontally over the stack, at least one set of coacting stack grippers comprising generally vertically disposed arms located on opposite sides of the stack, coacting guide members carried by the frame and connected to the gripper arms adjacent the tops thereof and overlying the stack, links pivotally connected to the arms and extending inwardly over the stack, a member to which the links are pivotally connected adjacent their inner ends, and means operatively engaging the member and adapted to move the same upwardly thus bringing the gripper arms into contact with the stack.

3. In apparatus for lifting a stack of bricks or the like, a main frame comprising spaced apart L-shaped members having legs disposed generally vertically along one side and generally horizontally over the stack, stack gripping means comprising at least two sets of generally vertically disposed arms with one arm of each set located on opposite sides of the stack and extending above the top of the stack, sets of coacting guide members secured to the sets of gripper arms near the top thereof and extending inwardly over the stack, means securing one of the coacting guide members of each set to the horizontal legs of the L-shaped frame members, sets of links pivotally associated with the gripper arms and extending over the top of the stack, independently movable sheave blocks carrying sheaves to which sheave blocks the inner ends of the sets of links are pivotally connected, an equalizing bar above the sheave blocks, sheaves on the equalizing bar, a cable having its

ends anchored and passing alternately under the sheaves in the blocks and over the sheaves on the equalizing bar, and means adapted to engage the equalizing bar and move the same upwardly thereby causing the gripper arms to clamp the stack therebetween.

4. Apparatus as defined in claim 3 in which the sets of coacting guide members each comprises a tube secured to the horizontal leg of the L-shaped frame member and connected adjacent its outer end to one arm of a set thereof, and a cylindrical member carried by the other arm of the set and fitting slidably within the tube connected to its associated arm.

5. In apparatus for lifting a stack of bricks or the like, a main supporting frame having elements disposed along one side and over the stack, stack gripping means comprising vertically disposed sets of arms located on opposite sides of the stack, lengths of tube secured to one of the arms of each set near the upper end thereof and extending inwardly toward the other arm of its set on the opposite side of the stack, cylindrical members secured to the other arm of the set on said opposite side of the stack and projecting slidably into said tubes, means operatively securing the tubes to the members of the main frame overlying the stack, sets of links pivotally connected at their outer ends to the arms, a sheave block for each set of links to which the inner ends thereof are pivotally connected, an equalizing bar mounted for vertical movement above the sheave blocks, sheaves carried by the equalizing bar, flexible means operatively connecting the sheaves whereby lifting force applied to the equalizing bar is transmitted substantially equally to the sheave blocks, and means engaging the equalizing bar and adapted to apply a lifting force thereto thereby bringing the arms into contact with the stack.

6. Apparatus as defined in claim 5 in which means is provided on the supporting frame for locking the equalizing bar in lowered position whereby upon applying said lift force to the equalizing bar the gripper arms remain in spread, stack receiving position.

7. In apparatus for lifting a stack of bricks or the like, a main frame having a vertical portion disposed on one side of the stack and adapted to rest on the surface supporting the stack, a horizontal main frame member connected to the vertical portion and extending over the stack, at least one length of tube carried by the horizontal member of the main frame and directed inwardly over the stack, a first stack gripping arm carried by and depending substantially vertically from the outer end of said tube alongside one side of the stack, a cylindrical member projecting slidably into said tube, a second stack gripping arm carried by and depending substantially vertically from the projecting end of said cylindrical member, links pivotally and operatively connected at their outer ends to said gripping arms and extending inwardly over the stack, a member to which the inner ends of said links are pivotally connected, and means operatively engaging the member at the inner ends of the links and adapted to move the same upwardly thereby moving the gripping arms into clamping engagement with the stack.

8. In apparatus for lifting a stack of bricks or the like, a main frame in the form of laterally spaced L-shaped sections having vertical legs which are longer than the height of the stack to be lifted, the other legs of said sections ex-

tending over the stack, lateral braces rigidly connecting the main frame sections, a plurality of sets of stack gripping arms each set of which comprises one vertically disposed arm rigidly connected adjacent its upper end to the main frame and depending therefrom at one side of the stack, a second arm for each set similar to the first named arm supported for sliding movement relative to the main frame toward and from the first named arm, links operatively connected to said arms and extending inwardly of the apparatus over the top of the stack, sheave blocks movable independently of each other to which the links of each set are pivotally connected, a flexible member passing under the sheaves of the blocks, an equalizing bar above the sheave blocks, said flexible member passing from the sheaves over members on the equalizing bar, and means engaging the equalizing bar and adapted to move the same upwardly thereby to clamp the stack and subsequent thereto lift the entire apparatus and the stack.

9. Apparatus as defined in claim 8 in which the main frame is provided with upstanding guide means restraining the equalizing bar to movement substantially vertically, and in which there is manually operated mechanism carried by said upstanding guide means effective when engaged to hold the equalizing bar in lowered position while the apparatus is being raised.

10. In apparatus for clamping and lifting a stack of bricks or the like, a main frame having sections L-shaped as viewed in end elevation with one leg thereof disposed alongside the stack to rest on the surface supporting the stack and with the other leg overlying the stack, lateral cross bracing securing the main frame sections rigidly together, a plurality of horizontally disposed lengths of tube carried by the main frame and projecting inwardly over the stack substantially parallel with the overlying legs of the main frame sections, gripper arms secured to the outer ends of the tubes and extending downwardly far enough to engage the bricks of the lower course at one side of the stack, members slideable in said tubes, other stack gripping arms secured to and depending from said slideable members and engageable with the bricks of the lower course on the side of the stack directly opposite the first named arms and adjacent the vertical legs of the main frame, inwardly directed pairs of links operatively connected to the arms for pivotal movement in vertical planes and extending over the top of the stack, independently movable members to which the inner ends of the links of each pair are operatively connected, and means positioned to apply lifting force substantially equally to the independently movable members thereby to move the gripping arms in clamping relation to the stack and subsequent thereto lift the entire apparatus and the stack.

11. Apparatus as defined in claim 10 in which there are stack clamping means at the ends of the stack, which means comprises laterally slideable vertically disposed gripping arms, means connected to the independently movable members and adapted upon upward movement thereof to move said end gripping arms into engagement with the ends of the stack, and other means connected to said independently movable member and adapted upon upward movement thereof to move the end gripping arms away from each other to stack receiving position.

12. In apparatus for lifting a generally cubical

stack of bricks or the like wherein the apparatus is translatable supported on a lifting vehicle, a main frame comprising at least one pair of L-shaped sections disposed with one of the legs thereof overlying the stack, the other legs being vertically disposed and long enough to hold the overlying legs spaced above the stack when the lower ends of the vertical legs rest on the surface supporting the stack, lateral cross bracing rigidly securing the sections together, tubes operatively connected to the main frame extending partially across the top of the stack and equaling in number the number of bricks in the lowermost course of the stack, downwardly and inwardly directed gripper arms secured to the outer ends of said tubes and adapted to contact the bricks of the lower course near the longitudinal center thereof, members fitting snugly in each of said tubes and slideable therein, gripper arms similar to the first named ones secured to the outer ends of said slideable members, a pair of links for each arm pivoted thereto at their outer ends for movement in vertical planes, sheave blocks for corresponding sets of said arms to which the links thereof are pivotally connected at their inner ends, an equalizing bar mounted for movement in a vertical plane above the sheave blocks, sheaves on the equalizing bar, a cable having its ends secured to the equalizing bar and passing alternately under the sheaves in the blocks and over the sheaves on the equalizing bar, means engaging the equalizing bar and adapted to apply a lifting force thereto thereby to move the sheave blocks and said links upwardly and move the gripping arms into contact with the lower courses of bricks, and manually engageable hold-down means operatively carried by the main frame disposed when engaged to hold the equalizing bar in lowered position when said lifting force is applied.

13. Apparatus as defined in claim 12 in which the hold-down means is normally biased to a position permitting the equalizing bar to move upwardly when the lifting force is applied thereto.

14. The combination with stack lifting apparatus of the type embodying sets of inwardly movable independently actuatable gripping arms disposed on opposite sides of the stack, of means to move said arms into contact with the stack comprising an equalizing bar disposed above the arms, sheaves on the equalizing bar, a sheave block associated with each set of gripper arms, sheaves in said sheave blocks, a cable having its ends anchored and passing alternately under the sheaves of the blocks and over the sheaves of the equalizing bar, means operatively connecting the sets of arms to their associated sheave blocks and effective upon upward movement of the blocks to move the arms into engagement with the stack, and means engaging the equalizing bar and adapted to move the same upwardly.

HERBERT J. NEHER.
